(57) **CLAIM**

The ornamental design for a basketball training ball, as shown and described.

DESCRIPTION

FIG. 1 is a perspective view of a basketball training ball showing my new design;

FIG. 2 is a second perspective view thereof;

FIG. 3 is a front view thereof;

FIG. 4 is a rear view thereof;

FIG. 5 is left side view thereof;

FIG. 6 is a right side view thereof;

FIG. 7 is a top view thereof; and,

FIG. 8 is a bottom view thereof.

The broken lines shown in the drawings depict portions of the basketball training ball that form no part of the claimed design.

The shade lines in the Figures show contour and not surface ornamentation.

1 Claim, 4 Drawing Sheets(56)
